UNITED STATES PATENT OFFICE

118,986

DESIGN FOR AN ADVERTISING DISPLAY DEVICE

Maxwell E. Ramsey, Clayton, Mo.

Original application June 12, 1939, Serial No. 85,457. Divided and this application December 11, 1939, Serial No. 88,813

Term of patent 3½ years

To all whom it may concern:

Be it known that I, Maxwell E. Ramsey, a citizen of the United States, residing at Clayton, county of St. Louis, State of Missouri, have invented a new, original, and ornamental Design for Advertising Display Device, of which the following is a specification, reference being had to the accompanying drawing, forming part thereof, in which—

Fig. 1 is a top plan view of an advertising display device showing my new design.

Fig. 2 is a front elevation.

This is a division of application Serial No. D-85,457, filed June 12, 1939, for patent for design for Advertising display device.

I claim:

The ornamental design for an advertising display device, as shown.

MAXWELL E. RAMSEY.
